UNITED STATES PATENT OFFICE

JULIAN B. CONNER, OF HUMBLE, TEXAS

FLOW TESTER

Application filed January 3, 1928. Serial No. 244,203.

This invention relates to new and useful improvements in a flow tester.

One object of the invention is to provide an apparatus of the character described, especially adapted to be let down into a well bore and effective to ascertain the character of fluid in a stratum being tested.

Another object of the invention is to provide an apparatus of the character described through which a sample of the fluid contained in a stratum in a well bore may be obtained and brought to the ground surface and the character of such fluid and the approximate amount of fluid borne by said stratum thus ascertained.

A further object of the invention is to provide an apparatus of the character described which is of very simple construction and may be easily manipulated and which is very efficient for the purpose intended.

With the above and other objects in view this invention has particular relation to certain novel features of construction, operation and arrangement of parts an example of which is given in this specification and illustrated in the accompanying drawings wherein:—

Figure 1 shows a vertical sectional view of the upper portion of the device.

Figure 2 shows a vertical sectional view of the lower portion thereof.

Figure 3 shows a cross sectional view taken on the line 3—3 of Figure 1, and

Figure 4 shows a cross sectional view taken on the line 4—4 of Figure 1.

Referring now more particularly to the drawings, wherein like numerals of reference designate similar parts in each of the figures the numeral 1 designates the tubular operating stem to the lower end of which the tubular actuating stem 2 is connected by means of the coupling 3. Fitted through the actuating stem 2 there is a tubular barrel 4 a section of which is provided with a continuous reversible thread 5.

Fitted over the actuating stem 2 there is a sectional housing 6 and the actuating stem has an annular external rib 7 which runs in an annular internal groove 8 provided between the upper sections of the housing, and

which prevents the endwise movement of the actuating stem relative to the housing. There is an elongated key 9 which has a pivotal connection with the actuating stem and which runs in between the turns of the thread 5, said turns forming a reversely spiralled continuous keyway.

The lower end of the housing 6 is formed into a valve cage 10 whose lower end has an annular internal flange 11 into which is threaded the tubular packer support 12 and on this support there is a suitable packer 13 which is clamped between the upper plate 14, which abuts the lower end of the cage 10, and the jamb nut 15 which is screwed onto the packer support and abuts the lower end of the packer. Screwed onto the lower end of the support 12 there is a perforated nipple 16 whose lower end is preferably closed.

The housing 6 has an internal chamber 17 beneath the actuating stem and around the barrel 4. This chamber is provided to contain a lubricant for the actuating stem and the barrel and for the thread 5 of the latter and this lubricant is retained against escape by means of the packing glands 18 and 19 around the barrel and actuating stem, respectively, above said chamber, and the packing gland 20 between the barrel and housing beneath said chamber. The lower end of the gland 20 forms a valve seat 21 which is normally closed by the downwardly opening valve 22. This valve is mounted on a coil spring 23, which, in turn, is mounted on a perforated support which is mounted on the flange 11.

The barrel is confined to a lengthwise movement in the housing by means of the keys 25, 25, carried thereby, which run in the inside lengthwise keyways 26, 26, in the housing 4.

The lower end of the barrel 4 is formed with a concaved valve seat 27, with the perforations 28 around said seat.

In making a test the bore of the well is usually reduced above the stratum to be tested, and the said stratum is pierced by the reduced bore.

The apparatus above described is then assembled as shown, with the valve 22 in closed

position and is let down into the bore and the packer 13 is seated against the shoulder formed on the wall of the bore, by reducing the same, so as to seal off the stratum to be tested. The bore will usually be filled with water, or "slush" and as the apparatus is lowered through it the valve 22, being seated, will prevent any fluid from entering the barrel or stem above. When the packer is set the stem 1 may be rotated to the right, and the actuating stem will be rotated with it and will operate through the key 9 and thread 5 to first drive the barrel downwardly until the seat 27 contacts with and opens the valve 22. The fluid in the stratum to be tested will then be forced by the pressure on said fluid, through the perforated nipple 16, opposite said stratum, and up through the packer support 12 and cage 10 into the barrel 4. A continued rotation of the stems 1 and 4 to the right will be effective, through the key 9 and thread 5 to reverse the direction of movement of the barrel 4 and said barrel will be lifted off of the valve 22 and said valve will be closed, by the spring 23, and the fluid in the barrel will be trapped therein and may be withdrawn, with the apparatus, to the ground surface for inspection.

If oil is found to exist in paying quantities in the tested stratum the casing may then be set in the bore and the well completed. If such oil is not found to exist the hole may be abandoned, or deepened without setting casing therein until paying oil is found.

The threads connecting the joints of the drill stem as well as those connecting the drill stem to the actuating stem and connecting the sections of the housing are usually all right hand threads and in opening and closing the valve 22, in operating the tester, the stems 1 and 2 being always turned to the right there will be no liability of unscrewing and separating any of the connected parts.

It is obvious that mechanical changes may be made in the structure and equivalents substituted for the parts shown and I reserve the right to make such mechanical changes, substitutions and adaptations as will not depart from the principle of the invention as comprehended within the scope of the appended claims.

What I claim is:—

1. Apparatus for testing a formation in a well bore including a string of pipe to be let down into the bore and having an inlet at its lower end, a packer carried by the pipe above said inlet, a valve for controlling the inlet, means operatively connected with the string and adapted to be actuated, by the rotation of the pipe, against the valve to open the valve, and to be released from said valve by a continued rotation of the string in the same direction, to permit the valve to close.

2. Apparatus for testing a formation in

a well bore including a string of pipe adapted to be let down into the bore with its lower end adjacent the formation to be tested, and having an inlet at its lower end, a valve controlling said inlet, means operatively connected with the pipe and operable by the rotation of the pipe in one direction to alternately open, and permit the closing of the valve and means for sealing the bore above said inlet and means constantly tending to close the valve.

3. Apparatus for testing a formation in a well bore including a string of pipe to be let down into the bore and having a fluid inlet at its lower end, means normally closing said inlet to prevent the fluid in the bore from entering said string while the same is being lowered, means operatively connected with the string and movable, in one direction, by the rotation of the string to effect the opening of said closing means, and movable in the other direction, by a continued rotation of the string, in the same direction, to permit said closing means to close.

4. Apparatus for testing a formation in a well bore including a string of pipe to be let down into the bore and having a fluid inlet at its lower end, means normally closing said inlet to prevent the fluid in the bore from entering said string while the same is being lowered, means operatively connected with the string and movable, in one direction, by the rotation of the string to effect the opening of said closing means, and movable in the other direction, by continued rotation of the string, in the same direction, to permit said closing means to close, and a packing element between said string and the well bore above said inlet.

5. Apparatus for testing a formation in a well bore including a string of pipe to be let down into the bore, and having an inlet at its lower end, a packer carried by the string above said inlet, a valve adapted to block said inlet, means normally holding the valve closed, a barrel in the string, operative connections between said pipe and barrel through which the barrel, by a one way rotation may be actuated against the valve to open said valve, and released from the valve by a continuation of said rotation in the same direction, to permit it to close.

6. Apparatus for testing a formation in a well bore including a string of pipe adapted to be let down into the bore and having an inlet at its lower end, means for sealing the bore around the string above said inlet, a valve normally closing said inlet, a barrel in the pipe, said pipe and barrel being provided, one with a continuous reverse keyway and the other with a key adapted to work in said keyway said key and keyway forming connections through which a continued rotation of the pipe, in one direction will operate to actuate the barrel against, and withdraw it

from, said valve, alternately to effect the opening, and permit the closing, of said valve.

7. Apparatus for testing a formation in a well bore including a string of pipe to be let down into the bore and having an inlet at its lower end, a packer carried by the pipe above said inlet, a valve for controlling the inlet, means operatively connected with the pipe and adapted to be actuated, by the rotation of the pipe, against the valve to open the valve and to be released from said valve by a continued rotation of the pipe in the same direction, to permit the valve to close, said pipe having an internal lubricant chamber adjacent said valve opening means.

8. Apparatus for testing a formation in a well bore including a string of pipe to be let down into the bore, and having an inlet at its lower end, a packer carried by the string above said inlet, a valve adapted to block said inlet, means normally holding the valve closed, a barrel in the string, operative connections between said string and barrel through which the barrel may be actuated against the valve to open said valve, and released from the valve, to permit it to close by a one way rotation of the string said apparatus having an internal closed, lubricant chamber about the barrel.

In testimony whereof I have signed my name to this specification.

JULIAN B. CONNER.
